UNITED STATES PATENT OFFICE

145,093

DESIGN FOR A TOY ROCKING HORSE

Bernard R. Mandelbaum, New York, N. Y., assignor to Wood Commodities Corp., New York, N. Y., a corporation of New York

Application October 17, 1945, Serial No. 122,918

Term of patent 3½ years

(Cl. D34—15)

To all whom it may concern:

Be it known that I, Bernard R. Mandelbaum, a citizen of the United States, residing at New York city, in the county of New York and State of New York, have invented a new, original, and ornamental Design for a Toy Rocking Horse, of which the following is a specification, reference being had to the accompanying drawing, forming part thereof.

In the drawing:

Fig. 1 is a perspective view of a toy rocking horse showing my new design;

Fig. 2 is a front elevational view thereof.

I claim:

The ornamental design for a toy rocking horse, substantially as shown.

BERNARD R. MANDELBAUM.
